UNITED STATES PATENT OFFICE.

HERBERT G. MACKINNEY, OF PROVIDENCE, RHODE ISLAND.

DESIGN FOR JEWELRY.

SPECIFICATION forming part of Design No. 12,619, dated December 20, 1881.

Application filed October 26, 1881. Term of patent 3½ years.

To all whom it may concern:

Be it known that I, HERBERT G. MACKINNEY, a citizen of the United States, residing at the city and county of Providence, State of Rhode Island, have invented and produced a new and original design for various articles of manufactured jewelry, such as charms, breast or other pins, ear-rings, &c., of which the following is a specification, reference being had

10 to the accompanying drawings, forming part thereof, in which—

Figure 1 represents a face view of an article which might be arranged to form a part of a locket, breast, shawl, or other pin, ear-ring, or 15 various other articles of ornamentation, provided with my proposed design. Fig. 2 is a view representing an article, such as a breast-pin, arranged or constructed so that my proposed design shall form the entire structure 20 thereof.

The object of my design is to (by some familiar universal article, such as jewelry ornamentation) remind and recall to the wearer an incident in a late popular play; and my said 25 design consists in the figure of the old upright

barrel-churn and a curved horseshoe-shaped figure intended to represent a horseshoe-magnet. These figures may, (as shown in Fig. 1, wherein A is the churn, with dash-rod *a*, and B the horseshoe-magnet,) be arranged in various positions, and either, as shown in Fig. 2, as alone forming the article or as associated with other figures, lines, &c., of ornamentation, as shown in Fig. 1.

The parts of the design may, as is apparent, 35 be arranged in various ways or positions in relation to each other without departing from the spirit of my invention.

The figures of the churn and magnet may be in relief or the reverse, as desired.

I claim—

The design for articles of manufactured jewelry, substantially as shown and described, wherein the figures of a churn and horseshoe-magnet form the distinguishing features there- 45 of.

HERBERT G. MACKINNEY.
